Attorneys

UNITED STATES PATENT OFFICE.

PHILIP E. GABRIEL, OF DETROIT, MICHIGAN, ASSIGNOR, BY MESNE ASSIGNMENTS, TO BOHN ALUMINUM & BRASS CORPORATION, OF DETROIT, MICHIGAN, A CORPORATION OF MICHIGAN.

RADIATOR-CAP CONSTRUCTION.

Application filed December 12, 1927. Serial No. 239,575.

The invention relates to closures and more particularly to closures for the filler tubes of automobile radiators.

Many of the advantages and much of the commercial value and acceptability of the invention is attributed to the novel construction of the closure member and the cooperating adapter ring, these advantages being obtained particularly because of the simplicity of the construction and the minimum number of parts employed. This enables the closure assembly to be economically and quickly manufactured and easily installed and renders the same strong and durable. The invention therefore, depends for some of its advantages, upon the specific details of construction illustrated and about to be described.

Other objects and novel features of construction which contribute materially to the mechanical efficiency of the apparatus will be made more apparent as this description proceeds especially when considered in connection with the accompanying drawings, wherein

Figure 1 is a perspective view of a closure constructed in accordance with my invention;

Figure 2 is a side elevation partly in section showing the closure in closed position; and

Figure 3 is a sectional view taken on the line 3—3 of Figure 2.

Referring now to the drawing wherein like reference characters illustrate corresponding parts throughout the several views, the numeral 10 designates the filler neck of an automobile radiator and the numeral 11 indicates an adapter ring threadedly mounted upon the filler neck and permanently secured thereto by means of the set screw 12, which as shown, threadedly engages the adapter ring and abuts the filler neck. With this arrangement, the adapter ring may be accurately positioned relative to the hood ridge construction (not shown). The adapter ring is also provided with an inwardly extending annular flange 13 spaced inwardly from the top surface 14 of the ring forming an L-shaped recess 15 adapted to receive a gasket 16 which may be of rubber, rubber composition or any suitable material. The adapter ring is further formed intermediate the inner face

of the flange 13 and threads 17 of the ring with an annular recess or groove 18 of a sufficient dimension to receive the member 19. As shown, this member is preferably formed of spring metal and in the present instance is shown as a piece of spring wire, the ends of which being spaced apart a substantial distance so as to yieldably force the arcuate portion 20 diametrically opposite the spaced ends, against the side walls of the groove 18. Arranged within the ring adjacent the forward edge thereof, is an aperture 21 which as shown, extends downwardly from the top surface 14 of the ring and intersects or opens into the groove 18 exposing a portion of the spring member 19. Hingedly mounted upon the ring diametrically opposite the aperture 21 is a closure member 22 having a depending projection 23 so positioned upon the latter that in the closed position of the same it will engage in the aperture 21 in substantial vertical alignment with the portion of the spring member 19 exposed by said aperture. As shown, the lower end of the projection 23 is rounded off as indicated at 24 and is formed adjacent to the rounded portion aforesaid with a groove 25, the arrangement being that when the closure is swung to closed position the rounded portion 24 engages the arcuate portion 20 of the spring member 19 and forces the same inwardly until the arcuate portion 20 is opposite the groove 25 at which time this portion will spring outwardly into the groove 25. To open the filler tube an upward force is exerted upon the closure member disengaging the arcuate portion 20 from the groove 25 and swinging the closure to open position.

Thus from the foregoing, it will be noted that the herein described closure is relatively simple and economical in construction and one that may be operated with facility.

While the invention has been shown and described in connection with the filler tubes of automobile radiators and while the illustrative embodiment of the invention is adapted for use upon such radiators, it should be noted that many of the objects and advantages of the present invention may be realized when the same is used in connection with various forms of containers and accordingly the invention contemplates such an arrangement.

What I claim as my invention is:

1. The combination with a filler tube of an automobile radiator and an adapter ring secured to said tube having an annular groove therein and having an aperture communicating with said groove, of a closure pivotally mounted upon said ring having a depending projection, and a spring member positioned within the groove aforesaid and extending 10 into said aperture, said member cooperating with the projection upon said closure to automatically latch the latter in closed position.
2. The combination with a filler tube of an automobile radiator and an adapter ring 15 secured to said tube having an annular groove therein and having an aperture communicating with said groove, of a closure pivotally mounted upon said ring, a spring member positioned within the groove aforesaid and extending 20 into said aperture, and a projection upon said closure adapted to register with said aperture when the closure is swung to closed position, said projection having a recess in one face thereof for receiving a portion 25 of said spring member when the closure is in closed position.
3. The combination with a container providing an opening therein and having a recess adjacent to said opening, of a closure for 30 said opening, means for latching said closure in closed position including a flexible member arranged within said opening and having a portion projecting into said recess and means projecting from said closure and 35 engageable with the projecting portion of

said member when the closure is in closed position upon the container.

4. The combination with a member having an opening therein and a recess positioned adjacent to said opening, of a flexible 40 ring positioned within said opening with a portion thereof projecting into said recess, and means carried by said closure adapted to move into said recess upon closing the closure and interlock with the projecting portion of said ring.

5. In combination a member having an opening therein with a groove in one wall thereof and having a recess positioned to one side of the said opening and communicating with said groove, a yieldable member disposed within said groove and having a portion projecting into said recess, and a closure for said opening having means operable upon closing the closure to move into said recess 55 and interlock with the projecting portion aforesaid of the yieldable member.

6. The combination with a member having an opening therein and having a recess positioned at one side of said opening and communicating therewith, a flexible member positioned within said opening and having a portion projecting into said recess, and a closure for said opening having means operable upon closing the closure to move into said recess 65 and interlock with the projecting portion aforesaid of the flexible member.

In testimony whereof I affix my signature.

PHILIP E. GABRIEL.
